UNITED STATES PATENT OFFICE

ALFRED WINSLOW HALL AND JOHN R. DONNELLY, OF PORTLAND, MAINE

AUDIPHONE

Application filed September 14, 1928. Serial No. 305,930.

Our invention relates to acoustic devices and applies more particularly to that type in which the power of audition of the individual using the instrument is enlarged by the reproduction and amplification of the sound waves transmitted to his ear by diaphragmal vibrations without resort to electrical means to augment the strength of the reproduced sound.

Such a device, for instance, as our present invention which, we believe, is an improvement on the one patented by us on September 14th, 1926, numbered 1,599,961, is especially adaptable for use by persons afflicted with impaired hearing, on account of its superior characteristics with respect to acoustical transmission, its portability, ease of application and simplicity in design and construction.

A general object of our invention, considered in terms of structure, is to provide an audiphone with such an arrangement of diaphragms and connected parts as will not only reproduce articulation in amplified form but in improved tonal quality.

A specific object resides in the interposition of an element, as for example, a pin, between two diaphragms, one preferably thicker than the other and constructed of identical or different materials, the interposed element being either fixed in one diaphragm and in abutting contact with the other, or suspended between the two so that, while normally in contact with both, it may upon extreme vibrations of either of the diaphragms become slightly separated from one or the other during the intervals between successive vibrations of the diaphragmal elements.

The thicker diaphragm would, if free to act alone, respond to the lower pitched tones and the thinner to the higher ones, but in co-action and interconnection they collectively produce a combination of controlled tones such, for instance, as does a bow when drawn simultaneously across the high and low pitch strings of a stringed instrument.

To illustrate our invention we have prepared the accompanying drawing which discloses the preferred embodiment thereof.

In this drawing,—

Fig. 1 is a sectional elevation of the audiphone, showing the diaphragm pin attached to one of the diaphragms;

Fig. 2 is a fragmentary sectional elevation of the same, with the pin suspended between the two diaphragms;

Fig. 3 is a fragmentary sectional elevation of a modified form of the device;

Fig. 4 is a detail view showing method of attaching the pin to one of the diaphragms;

Fig. 5 is a face view of the pin-holding element used when the pin is suspended between the diaphragms;

Fig. 6 is a side elevation of the part shown in Fig. 5;

Fig. 7 is a sectional view on line 7—7, Fig. 1;

Fig. 8 shows how the audiphone can be used in a head set;

Fig. 9 is a modified form of the device, incorporating a third diaphragm, and

Fig. 10 is a sectional view taken on line 10—10, Fig. 9.

Similar reference characters are employed to identify like parts in all views of the drawing.

Referring to Fig. 1, 20 represents the cylindrical body of the audiphone, an exterior screw threaded portion 21 on which serves to receive and secure the cap 22 thereon.

Within the cap is an outer diaphragm 23 and inner diaphragm 24, the latter being relatively thinner. Interposed between the outer margins of the diaphragms is an annular ring 25 which serves as a spacer and abutting on the thinner of the two diaphragms is the flange portion of the frustoconical member 26. The four last mentioned elements are secured between the shoulder 27 of the cap 22 and the face of the body 20 by screwing the cap on to the body until all are firmly seated.

Although the audiphone is operable with diaphragms made of various materials, we prefer either of two combinations,—first,—both of mica, and second,—the outside diaphragm of metal and the inside of mica.

The element about which we are most concerned in this present invention is the diaphragmal pin, hereinafter to be described, taken in connection with two diaphragms,—of whatever material made.

The cylindrical portion of the body is perforated by holes 28, and in axial and radial alignment with these are holes 29 in the member 26.

10 This member (26) is quite like a megaphone although operative in a different manner—the sound waves passing through from the larger to the smaller end. The opening in the smaller end aligns with the hole 30 in 15 the dished end of the body 20.

On the axis of the diaphragm 23 is a hole 31 in which a pin 32 is secured by means of the clamp nuts 33. This pin may be attached to the diaphragm in any one of various ways, but we prefer the nuts, one on each side, for the reason that they serve admirably to hold the pin in any particular position to which it is adjusted.

In Fig. 2 is illustrated a construction 20 which, although somewhat more costly, appears in practice to be an improvement on the method of allocating the pin in the device as shown in Fig. 1. An annular washer or collar 34 clamped at its marginal portions has an arm 35 extending to and slightly beyond its axis; to this arm the pin is secured, each end abutting on one of the respective diaphragms. The arm 35 is preferably sprung slightly toward the thicker 25 diaphragm when assembled in the audiophone so that a constant strain, tending to hold it in contact therewith is exerted. The pin in this instance may be made in one piece or of two, in which latter case it may 30 be made adjustable, one part telescoping the other.

In Fig. 9 is shown a modified form of our audiophone. The receiving end is identical with the corresponding parts in the type 20 shown in Fig. 1, but the body 20 is discarded or replaced by the member 26. The smaller or delivery end terminates in a transverse flange 36 having threaded engagement with the cap 37 at 38.

Locked at its outer margins, between the cap 37 and the flange 36 is a third diaphragm 39 having therein an aperture 40 disposed in axial alignment with the opening 41 in the cap. The diaphragm is free to 45 vibrate in the space 42.

The concaved formation of the delivery end of the body 20 of the audiophone is so as to better enclose the user's ear when placed thereover, but we have ascertained that in certain cases of extreme deafness of the individual beneficial results are obtained by extending the member 26 outwardly a short distance from the body of the audiophone, this extension entering the space in 50 the ear and providing a greater concentra-

tion and intensification of the sound waves close to the ear drum. This idea is shown in Fig. 3.

Much time and energy have, from time to time, been expended by numerous inventors in the conception and development of devices of a somewhat similar nature to that of the present invention. In most cases the object sought has been attained with a clear perception of the principles involved in the accomplishment, but in other instances the question as to just how the means employed brought about the successful result in experimentation has arisen.

Our understanding of the function of the pin 32, its operative relationship to the diaphragms and the exact part it plays in the whole combination may, or may not be in strict accord with advanced scientific reasoning.

However, after disclosing the method we employ in locating this pin in the structure, particularly in relation to the diaphragm 24, we will recite what we believe to be consistent reasons for its accomplishing the marked improvement which it has actually made in the acoustical quality of our audiophone.

We will repeat what we have already stated, that the two diaphragms, 23 and 24 are bound rigidly at their outer margins and before the pin 32 is adjusted to its proper place, the faces of the diaphragms or discs are flat and parallel, relatively. The pin is brought into contact with the diaphragm 24 by means of the actuation of the inner nut and forces it outwardly very slightly, throwing its face out of a flat plane. On the flexing of this diaphragm the proper amount, depends the tonal quality of the reproduced sounds. By forcing the pin outwardly to too large an extent, the soft tones produced by the slower vibrations are lost, and if not extended sufficiently the diaphragm will vibrate excessively and harsh reproductions and distortion of the sound waves result.

Thus it will be seen that, when the diaphragms are at rest, there is an intermediary element making contact with both of them, and that this contact is broken only when the diaphragm 24 vibrates sufficiently to separate it from the point of the pin.

The heavier or slower vibrations of the sound waves act on the thicker diaphragm and are communicated, through the agency of the pin, to the thinner one which, not being attuned or in step with these slower moving waves, sharply moves in response to the axial movements of the pin caused by the heavy vibrations of the thicker diaphragm.

But when higher pitched sound waves envelop the audiophone they reach, in passing through the holes 28 and 29 the more elastic diaphragm 24 which responds with a more

pronounced and rapid vibration and delivers to the listener's ear the reproduced sounds of higher register.

An important point to consider in connection with the vibratory action of the diaphragm 24 is the fact that a thin disc may be made to vibrate so rapidly that synchronism between the original and the reproduced sound waves is lost. In the present 10 instance, the diaphragm 24 cannot reach this point of excessive vibratory action for the reason that it is held in check by the pin 32—the vibration being confined to one side of the plane in which the disc is secured. 15 There seems, therefore, to be a coordination between the two diaphragms and the pin which tends to somewhat intensify the moderate tones and smooth down the harsh ones—a compromise, as it were, serving to 20 increase the audibility of the reproduced sounds.

The modified form of the audiphone shown in Fig. 9 includes an additional diaphragm and in tests made of this type there apparently was an augmentation in the power of the reproduced sound waves, due doubtless to the fact that this style body is considerably longer and the taper of the conical member 26 more acute than corresponding 25 elements in the type shown in Fig. 1. There is also a probability that the impingement of the sound waves through the member 26 directly on the central portion of the diaphragm 39 conduces to a more intense vibration of the latter than possibly would be the case if its whole area exposed to a less concentrated impact of these waves. The object of the central hole 40 in the diaphragm 39 is so as not to choke the movement of the air 30 within the body 26, this surmise being based on the fact that improved results obtained with the hole which were lacking without it.

We consider, however, that the arrangement shown in either Figs. 1, 2 or 3, to be a preferable embodiment of our invention, chiefly because it is of simple construction, compact in form and effective in operation. And while we have disclosed in this application the function of the pin operable between 45 two diaphragms as specially applicable to portable audiphones, we desire to be understood that we do not restrict ourselves to its use for this particular purpose, as obviously, other uses may be found wherein the principle involved in its present application can be utilized.

Having described our invention, what we claim and desire to secure by Letters Patent is:—

60 1. An audiphone comprising in combination a hollow body member having perforations in the wall thereof, an inwardly-dished end on said body having an aperture therethrough, a diaphragm, a second diaphragm, 65 an annular ring adapted to hold said dia-

phragms in spaced relation, relatively, an annular cap securing said diaphragms and said annular ring to said body member, and a pin disposed interjacent and axially of said diaphragms and having each end unattached to and in normal contact with, but subject to intermittent separation from its adjacent diaphragm when vibrations of the latter occur.

2. An audiphone comprising in combination a cylindrical body having a dished end, an aperture in said dished end concentric with its axis, a frusto-conical member within said body, the smaller end thereof extending through and for a spaced distance beyond the aperture in said dished end, perforations in the wall of said cylindrical body, perforations in said frusto-conical member aligning, respectively, with the perforations in said body, two diaphragms relatively spaced and of dissimilar thicknesses secured, at their outer margins only, to the full-open end of said body, and a pin suspended between said diaphragms with each end thereof normally contacting with its respective and adjacent diaphragm but subject to intermittent disengagement therefrom during vibrations of said diaphragm.

In testimony whereof we affix our signatures.

ALFRED WINSLOW HALL.
JOHN R. DONNELLY.
